CLAIM

The ornamental design for a combined door stop and
wall patch combination, as shown and described.

DESCRIPTION

FIG. 1 is a perspective view of a combined door stop
and wall patch, showing my new design;

FIG. 2 is a front elevational view thereof;

FIG. 3 is a rear elevational view thereof, a portion of
the removable cover folded back for clarity of illustration;

FIG. 4 is a side elevational view thereof; and

FIG. 5 is a cross-sectional view thereof.

Fig. 1.
